COMPOSITE CARD FLAT

Frederic E. Banfield, Jr., Whitinsville, Mass., assignor to Whitin Machine Works, Whitinsville, Mass., a corporation of Massachusetts

Application May 29, 1948, Serial No. 30,133

1 Claim. (Cl. 19—113)

1

This invention relates to card flats as used in revolving flat carding machines. Such flats support portions of card clothing which coat with the rotating carding cylinder. The flats are of very substantial length, and unusual strength and rigidity is necessary for their successful operation.

It is the object of my present invention to provide a composite card flat in which these qualifications are exceptionally well attained. To the accomplishment of this general object, I provide a card flat having a strong and rigid structural steel body portion and having separately formed and attached end portions which provide the required bearing and guiding surfaces.

My invention further relates to arrangements and combinations of parts which will be herein-after described and more particularly pointed out in the appended claim.

A preferred form of the invention is shown in the drawings, in which

Fig. 1 is a partial plan view of a composite card flat embodying my invention;

Fig. 2 is a side elevation thereof, with certain parts shown in section;

Fig. 3 is an end view, looking in the direction of the arrow 3 in Fig. 2; and

Fig. 4 is a transverse sectional elevation, taken along the line 4—4 in Fig. 2.

Referring to the drawings, my improved card flat comprises a structural steel body portion 10 which is preferably of the commercial T section shown in Fig. 4. Separately formed end portions or seats 12 are secured to the two ends of the body portion 10, and the card clothing C may be attached to the top surface 14 of the body member 10 in any convenient manner, as by clamping strips 15 (Fig. 3).

The end portions or seats 12 may conveniently be cast or molded from sintered or powdered metal and are preferably of more or less porous construction, so that they may be impregnated with a suitable oil or other lubricant.

Curved guiding surfaces 16 on the seats 12 engage corresponding fixed surfaces in the carding machine and guide the flats in their desired spaced relation to the carding cylinder. Studs 18

2

are provided for attaching the flats to suitable transporting chains.

The end of the upright middle flange 10a of the steel body member 10 is preferably cut away as indicated at 20 in Fig. 2, and each end portion or seat 12 is secured to its body portion 10 by welding or brazing along the surfaces 20, 21 and 22 (Fig. 2). A firm and secure assembly of the three parts of each card flat is thus attained.

10 The structural steel body portion 10 is of much more firm and rigid construction than the cast iron construction previously commonly used, and the end portions or seats 12 may be economically formed and may be made of the metal which is best adapted to their intended purposes.

In case one of the seats 12 is broken or otherwise damaged, it may be removed and replaced, whereas with the previous construction the entire flat had to be discarded.

20 Having thus described my invention and the advantages thereof, I do not wish to be limited to the details herein disclosed, otherwise than as set forth in the claim, but what I claim is:

25 A composite card flat comprising a structural steel T-bar and pre-formed end seating members rigidly and permanently secured to the ends of said T-bar, the end portions of the middle flange of said T-bar being entirely cut away to provide flat seating surfaces for said end members, and 30 said end members being secured in abutting relation to said flat surfaces and to the transverse end faces of said T-bar and said middle flange.

FREDERIC E. BANFIELD, JR.
